UNITED STATES PATENT OFFICE.

DANIEL BARTLETT, OF EL RENO, OKLAHOMA, ASSIGNOR TO CHARLES ROBERT BENDIG,
OF PHILADELPHIA, PENNSYLVANIA.

HAIRPIN.

Application filed February 14, 1925. Serial No. 9,229.

This invention relates to new and useful improvements in hairpins.

One object of the invention is to provide a hairpin wherein the legs are so formed 5 that they interlock with each other, and with the hair, whereby the pin will not become easily disengaged from the hair.

Another object is to provide a hairpin wherein the legs are formed with helix 10 turns coiled in opposite directions, and wherein the alternate opposite pairs of turns overlap from opposite sides from the adjacent alternate pairs.

Other objects and advantages will be apparent from the following description when taken in connection with the accompanying 15 drawing.

In the drawing:

Figure 1 is a front elevation of a hairpin 20 made in accordance with the present invention.

Figure 2 is a side elevation of the same.

Figure 3 is a horizontal sectional view on the line 3—3 of Figure 1.

Referring particularly to the accompanying drawing there is shown a hairpin which is formed from a single length of suitable wire, and includes the leg portions 10, connected at one end by the curved bight portion 11. For a suitable distance from the bight portion, each of the legs is straight, as shown at 12, and is parallel with the other leg. The free end portions, for a suitable distance, are also straight and parallel, as shown at 13. The portions of the legs connecting these straight portions are formed with the helix turns 14, those of one leg being coiled in the opposite direction to those of the other leg, as clearly seen in the 40 drawing, there being three helix turns in

each leg. The first pair of turns, or those joined directly to the straight portions 12, are overlapped to a certain distance, as are also the other end pair, and the intermediate pair, it being noted, however, that the first 45 pair and the last pair overlap in the same direction, while the intermediate pair overlap in the opposite direction thereto. There is thus formed a tortuous path longitudinally between the legs in the plane of the legs, 50 and a second tortuous path in a plane at right angles to the first plane. Thus, when the legs of the hairpin are thrust into the hair the hair is securely interlocked with the overlapped helix turns thus holding the pin 55 against slipping from the hair, or being withdrawn therefrom, except by the exercise of mild force.

What is claimed is:

1. A hairpin including leg portions each 60 having a series of helix turns, the helix turns of one leg portion being coiled in the opposite direction to that of the helix turns of the other leg portion, said helix turns of one leg overlapping the helix turns of 65 the other leg in approximately the plane of the legs.

2. A hairpin including leg portions connected at one end by a bight portion, the portions of the legs adjacent the bight being straight and parallel, the free ends of the legs being straight and parallel, the intermediate portions of the legs being formed with oppositely coiled helix turns, every alternate opposite pair of which turns are 75 overlapped in a direction opposite to that of the other alternate opposite pairs.

In testimony whereof, I affix my signature.

DANIEL BARTLETT.
